RAILROAD HEATER

Walter G. Weisse, East Longmeadow, Mass., and Philip F. Farnigietti and Peter J. Vozzola, Windsor Locks, Conn., assignors to United Aircraft Corporation, East Hartford, Conn., a corporation of Delaware

Filed June 14, 1965, Ser. No. 463,707

3 Claims. (Cl. 219—213)

This invention relates to heaters and more particularly to electrical heaters mounted on the switching tracks of a railroad.

As is generally well known in the art, maintaining railroad switches free from snow and ice resulting from inclement weather has been an acute problem confronting the railroad industry for many years. Methods for insuring the operability of the switches during freezing weather have been done principally by employing such devices as (1) oil pots or natural gas fire schemes, (2) attaching electric heaters (generally of the Cal-rod type) by clamping the Cal-rod directly to the transverse wall of the switching rail, and (3) by manually chipping the ice away from the switches. All of these methods are not only cumbersome but present, in varying degrees, installation, maintenance, operation and economy problems. Utilizing an electric heater of the Cal-rod type not only is inefficient in this application because of poor heat transfer characteristics but also tends to weaken the rail itself by virtue of its associated attachment mechanism.

Another serious problem attendant to railroad switch heaters is that the heating element in certain installations has to be mounted to the track under adverse weather conditions. That is to say, in some instances the heater must be applied to existing operational switches that are exposed to the open environment in whatever temperature extremes that environment may impose (particularly cold weather). Thus, it was desirable to provide a heater which could be installed under ambient temperature conditions of as low as -40° F., while still maintaining the switch operational.

Under such conditions, it is important that the heater be capable of providing sufficient heat into the rail to raise the rail temperature from ambient temperature to at least 50° F., for operational effectiveness.

At the other extreme (high ambient temperature) it is necessary that the materials utilized in the basic heater, bonding agent, and surface treatment agents be capable of withstanding relatively high operating temperatures (say 400° F.) during those heater "on" periods when the ambient temperatures have risen above freezing conditions but the heater has not been turned off.

A system was found to satisfy these conditions by providing a conductive heating element imbedded in a plastic material and bonding the material directly to the switching portion of the rail.

It is therefore an object of this invention to provide a railroad switch heater comprised of a heating element imbedded in a substantially rigid reinforced plastic material.

A still further object of this invention is to provide a railroad switch heater that is intimately bonded by adhesives to the track portion of the switch track.

Other features and advantages will be apparent from the specification and claims and from the accompanying drawings which illustrate an embodiment of the invention.

FIGURE 1 is a top plan view of a railroad switch track diagrammatically showing the electrical circuit.

FIGURE 2 is a perspective view illustrating the heater in position.

FIGURE 3 is a side elevation partly in section illustrating the details of the heater.

2

FIGURE 4 is a section taken along 4—4 of FIG. 3.

FIGURE 5 is an end view of the heater shown in FIG. 3.

Referring now in detail to FIGS. 1-5, the railroad track of the usual I-beam construction is indicated by numeral 10 and includes rail head portion 12, bottom support flange portion 14, joined by the vertical transverse web 16. The heater is firmly bonded to the transverse wall 16 in a manner to be fully described below.

The terminal lead wires are connected in any suitable manner to an electrical supply source generally indicated by numeral 18. A contact switch 20 serves to open and close the circuit when the heater is placed in the operative and inoperative condition.

According to this invention, the heating element is suitably imbedded between woven glass fabric reinforced plastic forming the heater body 22. Preferably two layers of the woven glass fabric are placed under the heater element 23 and one layer is placed over the heater element 23. The woven glass fabric is then impregnated with suitable resins in any well-known manner to form a substantially rigid body. The method of molding a heater into the reinforced fabric may be accomplished by any of the more common systems presently available in industry such as press molding, vacuum bag/wet lay-up, hand lay-up, injection molding or vacuum injection molding. The particular systems that have been used in development of this invention are press molding and injection molding. In each case, the laminating resins employed were polyester base materials suitable for continuous operation at high temperatures.

Glass fiber cloth in tape form (Style 181 or 211) was used as the reinforcement agent. Epoxy and silicone base resins can be used in the application, as well as polyester resins.

Fixed to one end of the heater body 22 by any suitable means is the housing 24 which contains therein the electrical connection terminal lug 30, which carries power from the source 18 through cable 40 to the heater element through the electrical terminal conductor 42 (via rivet attachment 26), to the heating element 23.

Disposed between terminals 28 and 32 is thermostat 34. Thermostat 34 may be of any well-known type and for the purposes of illustration is shown to be comprised of a bimetal element 36 connected to terminal 32 and contact member 38 connected to terminal 28, and serves to open the circuit whenever the temperature of the heater reaches a predetermined (high) value for a sustained length of time and to reestablish circuit continuity when the heater temperature reduces to a lower temperature plateau.

The heater may be made up of a series of heater bodies similar to heater body 22 which are connected together externally by cable 40 with either a series or parallel circuit arrangement.

As noted from FIG. 5, the attaching surface 60 of the heater body is formed slightly convex to conform and complement the radius of the transverse wall 16. It is essential that contiguous and intimate contact be made at this point to ensure good and uniform heat conductance to the rail from the heater.

Woven graphite or carbon fabric commercially available from National Carbon Company, Division Union Carbide, New York, N.Y. or Basic Carbon Company, Sanborn, N.Y. may be used as the heater element 23, as well as wire element copper alloy resistance type wire.

The method of attaching the heater to the rail will be described hereinbelow. While this method is the preferred one which has been tested and proven to be suitable for keeping the track free from ice and snow, it is to be understood that any suitable bonding techniques that give like characteristics are considered to be within the scope of this invention.

RAIL AND HEATER SURFACE
PREPARATION

(1) The inner web surface area of the rail to which the heater is to be bonded shall be sandblast-cleaned to remove all traces of scale and surface contamination. It may also be advantageous to sandblast the outer web surface area in order that insulation foam can be bonded to that surface for the purpose of heat containment in the rail. Degreasing by means of a solvent and wiping with a dry lint-free cloth is desirable following the sandblasting and just prior to the bonding.

(2) Once the surface is sandblasted, the bonding operation must be performed within two (2) hours unless a protective coating is applied to the rail. The coating is required because of the high corrosion susceptibility of the rail metal alloy. A suitable coating is S-142F from B. F. Goodrich.

(3) Prior to application of the actual heater, the coating (if one exists) should be removed by peeling same free of the rail. At this time, use of a primer is recommended. The primer will provide a bondable surface and will not require removal or any subsequent preparation except light sanding and cleaning. A suitable primer, commercially available, is Silastic RTV 1201 Primer from Dow Corning.

(4) Wipe the heater surface with a lint-free cloth and methyl-ethyl-ketone (MEK) prior to the adhesive application.

BONDING OF HEATER

(1) Apply a uniform film of thermosetting adhesive, spread or brushed, 15-20 mils thick to the heater surface. A suitable adhesive is Silastic 732 which is thermosetting commercially available from Dow Corning. Uniformity is essential to prevent the creation of voids of entrapped air which product "hot spots" in the bond line.

(2) Install the adhesive coated heater by contacting one end onto the rail surface and "laying" into contact linearly until the opposite end is in place.

(3) Apply a clamping board centrally on top of the heater and clamp in position with C clamps placed every foot (minimum) along the heater. Apply the clamps, starting at one end, and clamp each succeeding clamp in sequence to avoid air entrapment.

(4) Apply nominal positive pressure with the clamps to maintain contact and alignment of the assembly. Apply final pressure when all clamps are in place. A uniform bead of adhesive should appear along the entire heater edge.

(5) Repeat steps (1) through (4) for subsequent heaters.

(6) Attach leads between the heaters.

(7) Attach the power lead from a suitable source to the extreme end of the first heater and attach the ground lead to the extreme end of the last heater.

(8) Apply an insulating blanket over the entire assembly.

(9) Cure the heater for 30 minutes at a bondline temperature of approximately 200° F. by energizing the heater.

(10) Check the bead of adhesive around the heater. The bead will harden when the initial cure is obtained.

(11) Remove the clamps and allow the heater to be activated for an additional one-half hour.

5 It is apparent from the foregoing that the heater must contain certain characteristics which are critical to the method of preventing snow and/or ice from accreting on the rail yet will not interfere with the operation of rail switching. The material between web 16 and heater element 23 must exhibit a dielectric strength between 1/2 and 20 megohms. The watt density of the heater must be between 8 to 18 watts per square inch. Additionally, the adhesive and material surrounding the heating element must be corrosion free, weather resistant and erosion resistant.

10 It should be understood that the invention is not limited to the particular embodiments shown and described herein, but that various changes and modifications may be made without departing from the spirit or scope of this novel concept as defined by the following claims:

15 We claim:

20 1. An electrical heater for a railroad switch track which track has a rail head, a support flange member and a vertical transverse web joining the rail head to the support flange member, said heater including a rigid elongated relatively thin body portion formed from a plurality of flat layers of glass fabric reinforced plastic consisting of at least one resin being selected from the group consisting of silicone, epoxy and polyester, an electrical resistive element having a watt density in the range of 8 to 18 watts per square inch mounted between said layers of said glass fabric reinforced plastic and spaced from said vertical transverse web, thermosetting adhesive means bonding said glass fabric reinforced plastic to said vertical transverse web, said adhesive means and said glass fabric reinforced plastic being characterized as being weather, corrosion and erosion resistant, an electrical power source and means for connecting said electrical resistive element to said electrical power source.

25 2. An electrical heater as claimed in claim 1 wherein said thermosetting adhesive means is formed from a silicone base.

30 3. An electrical heater as claimed in claim 1 wherein said glass fabric reinforced plastic adjacent said vertical transverse web has a dielectric strength falling in the range of 1/2 to 20 megohms.
